Application November 19, 1935, Serial No. 50,482

28 Claims. (Cl. 166—15)

This invention pertains to improvements in well pipe packing heads used for the purpose of sealing around work extending through the head into the well pipe. The work may consist of a 5 drill pipe, kelly, or one of various types of members depending upon the particular operation being carried out, and to all of which the present packing head is generally applicable. In addition to being adaptable for sealing around the 10 work during drilling operations, or around pipe during pipe setting or removal operations, our improved forms of heads may also be used as blow-out preventers. To those skilled in the art, the various uses and situations to which the 15 invention is adaptable, will be readily apparent.

The invention deals particularly with packing heads in which a compressible packer is pressed into engagement with the work by a contractor, 20 preferably in the form of a piston, that is movable vertically within the housing. Under certain conditions, the well pipe fluid pressure may operate the contractor to cause the packing to seal around the work, while under other conditions, the packing contractor may be similarly actuated by pressure fluid forming an independent 25 source of supply. Due to the difficulty sometimes encountered in releasing the packing from the work once it has been tightly pressed into engagement therewith, we have also provided fluid pressure operated means for actuating the contractor in its packing releasing movement. Our improved means for releasing the packer by fluid 30 pressure is of particular advantage in that it is capable of operation by fluid pressure not exceeding that existing in the well pipe, despite the fact that at the time, the high pressure within the well pipe may be acting against the contractor, tending to constrict the packer about the work. In its preferred form, the invention involves the provision of differential pressure areas 35 on the contractor piston and to which high pressure fluid from the well pipe, or some suitable independent source, is selectively applicable, in order to actuate the piston against the well pipe pressure to release the packer, and if desired, to operate the piston in its packing constricting movement independently of the well pressure.

It is one of the major objects of the invention to provide a highly efficient and reliable blow-out preventer that is capable of responding automatically and immediately to sudden increase in the well pipe pressure, to establish a fluid tight seal around the work. Generally speaking, our improved blow-out preventer includes a packer that is constrictible about the work, and means

responsive to well pressure increases, for constricting the packer. In its preferred form, the blow-out preventer comprises a packer, a packer contractor or constricting means, typically and preferably a piston movable vertically within the packing head, and a second packer, one preferably carried by the contractor, that renders the latter responsive to pressure increases to close the first mentioned packer, by maintaining a fluid restricter, or a positive seal, between the contractor and the work.

An additional feature of the invention resides in the provision of an improved dual assembly of packing heads in tandem arrangement adapted to pass collared pipe into or out of the well without losing the fluid seal around the pipe. Generally speaking, the two packers are operated and controlled so that, for example, as a collared section of pipe is being withdrawn from the casing with the lower packer open and the upper packer closed, when the collar has passed up through the lower packer, the latter is caused to close about the pipe and the upper packer is caused to then open to permit the collar to pass up through. A reverse sequence of operations occurs during lowering of the collared pipe through the packers. As will hereinafter appear, the packers may be controlled either manually or automatically; in the latter instance, by a control mechanism that is actuated by the pipe collar upon reaching a predetermined vertical position relative to the packers, all in a manner causing the packers to open and close in the sequences described.

In certain of its aspects, the present invention may be regarded as an improvement on the type of packing head disclosed in a copending application, Ser. No. 548,839, filed July 6, 1931 by Frederick Stone on Packing head.

All the above mentioned features of the invention, as well as additional objects and the details of certain illustrative and typical forms thereof, will be explained more fully and understood to better advantage from the following description. Reference is had throughout the description to the accompanying drawings, in which:

Fig. 1 is a longitudinal sectional view showing a typical form of combined packing head and blow-out preventer embodying the invention, the packing contractor being shown in released position; 50

Fig. 2 is a view similar to Fig. 1, showing the contractor in raised position, constricting the packer about the work;

Fig. 3 is a reduced scale elevation of the packing head showing diagrammatically the fluid 55

pressure connections with the piston chambers and the valve control;

Fig. 4 is a fragmentary view showing the packing carried within the lower portion of the contractor, radially expanded by engagement with the pipe collar;

Fig. 5 is a plan view of the lower packing ring assembly in its normal or constricted condition as shown in Fig. 1;

10 Fig. 6 is a view similar to Fig. 5, showing the packing in radially distended condition;

Fig. 7 is a fragmentary section similar to Fig. 4, showing a variational form of the contractor carried packing;

15 Figs. 8 and 9 illustrate a further variational form of packing carried by the contractor, in normal condition and after engagement by the collar, respectively;

Fig. 10 is a sectional view similar to Fig. 1, 20 showing a variant form of packing head adapted to take work, such as a grief or drive stem, of polygonal cross section;

Figs. 11 and 12 are sections on line 11-11 and 12-12, respectively of Fig. 10;

Fig. 14 is an elevation, diagrammatic in parts, showing a dual assembly of packer heads in tandem arrangement, with manually controlled 30 means for operating the respective packers;

Fig. 15 is an enlarged longitudinal section showing the control mechanism between the two packer heads in Fig. 14;

Fig. 16 is a view similar to Fig. 14, showing an 35 automatically controlled system for operating the packers; and

Fig. 17 is a fragmentary enlarged section on line 17-17 of Fig. 16.

The form of the invention shown in Figs. 1 40 and 2 comprises a packing head, generally indicated at 20, attached to the upper end of a well pipe or casing 21 by a threaded joint at 22, or in any other suitable manner. The packing head assembly comprises a tubular body or housing 23 having a lower reduced diameter bore 24 and an upper counterbore 25, there being a downwardly tapering shoulder 26 between the two bores. A tubular head 27 having a reduced diameter bore 28, counterbore 29 and intermediate 45 tapered bore 30, is threaded at 31 into the upper end of the housing. Although the head 27 is capable of vertical adjustment, if for any reason such adjustment is found desirable, it will ordinarily be screwed fully down to seat flange 27a on shoulder 23a. Fluid leakage from within the housing around the head is prevented by suitable means, such as a double lipped packing ring 33.

The tubular head 27 conveniently provides a mounting for a radially compressible rubber packer 34, which preferably takes the form of a sleeve having a substantially uniform diameter bore 35 with beveled surfaces at 36 and 37, an outer and upper cylindric surface 38, and a downwardly tapering or conical surface 39. The 50 lower end of the packer 34 has an annular groove 40 forming lips 41 and 42 which are adapted to be radially pressed into sealing engagement with the work 43 and the contractor piston 44, respectively, by fluid pressure applied against the 55 lower end of the packer. The packer may be mounted on the lower end of head 27 in any suitable manner, typically by means of a ring 45 attached to the lower end of the head sleeve 27b by lock balls 46, and fastened to the upper end 70 of the packer by looped reinforcing cables 47

having their ends terminating and secured within the ring, as illustrated.

The packer contracting piston 44 has upper and lower portions 44a and 44b of differential diameters corresponding to the diameters of the housing bores 25 and 24, respectively, the piston having a sliding fit within the housing and carrying suitable packing rings 48 to prevent fluid leakage. The angularity of the intermediate tapered surface 49 of the piston is somewhat greater than the angularity of the housing shoulder 26, so as to provide an annular space at 50 between the piston and housing, for the introduction of pressure fluid for purposes later to be explained. In its lowermost position, piston 44 seats on annular surface 26a, see Fig. 2, the angularity of which corresponds to the taper of the piston surface 49.

The contractor 44 has a bore 51 of substantially the same taper as surface 39 of the packer, 20 so that as the contractor moves upwardly relative to the packer, it acts to constrict the latter radially inward against the work 43. The relative positions of the contractor 44 and packer 34 in constricted condition are illustrated in Fig. 2, wherein the rubber is shown to be compressed against the pipe 43 and upwardly into the space 52 between ring 45 and the pipe, the ring bore being rounded at 45a to avoid tearing the packer.

The lower depending portion 27b of the tubular head 27 is spaced at 53 from the wall of the housing to provide an annular space containing a floating piston 54, which bears against the upper end of the contractor 44. The purpose of piston 54 is primarily to communicate to piston 44 the pressure of fluid introduced to chamber 53, as will be later described. It will suffice to state at this point that as a result of fluid pressure applied to piston 54, the contractor 44 is moved downwardly for example from the position of Fig. 2 to that of Fig. 1, to release the packer from the work. Accordingly, in certain aspects of the invention, piston 54 may be regarded as a part of the packer contracting and releasing means. It is made separate from piston 44 primarily for convenience of assembly. In order to facilitate removal of the entire packer and piston assembly from the housing by unscrewing and lifting the head 27, we provide within the upper end of the contractor 44 one or more keys 56, see Fig. 13, projecting inwardly in overlapping relation to ring 45, so that as the head and packer assembly is lifted, the ring is caused to engage keys 56 and lift the contractor piston out of the housing.

Suitable adjustable stop means is provided in conjunction with the head 27, to limit the upward travel of the piston assembly, and also to limit the degree to which the packer is constricted about the work, independently of the amount of fluid pressure being exerted upwardly against the contractor to compress the packer. The adjustable stop means may be of any suitable character, and is shown typically as comprising a plurality of circularly arranged set screws 57 extending through the head 27 and ring 58 into space 53 within the housing. Individual packing rings 59 prevent leakage of the high pressure fluid around the set screws. Normally, screws 57 will be set to limit the upward travel of pistons 44 and 54 at a point at which the packer 34 will be constricted about the work with sufficient tightness to prevent any considerable upward leakage of fluid, but at the same time to permit just enough fluid leakage through the packer to

lubricate its engagement with the work, so that packer wear as a result of rotational or longitudinal movement of the work will be reduced to a minimum. Chamber 190, enclosed by the piston 5 and head 27 above the packer is vented to the atmosphere, via bore 28, through passage 191. Consequently, any fluid leakage past the piston into chamber 190 will be expelled, so as not to interfere with the piston operation.

10 We also provide, in conjunction with the piston assembly, a means whereby the driller may ascertain the relative positions of the packer and contractor at any time valve 95 is feeding pressure fluid to the piston through pipe 96 or 97, without 15 having to disassemble the packing head, or without having to rely upon such uncertain indications as the amount of fluid leakage occurring when the packer is not tightly contracted about the work. While any suitable type of indicating 20 means may be used within the broad contemplation of the invention, we have shown a typical indicator in the form of a rod 60 connected at 61 to piston 54 and extending upwardly through bores in the ring 58 and head 27, fluid leakage 25 past the indicator rod being prevented by suitable packing at 62. If desired, the upper portion of rod 60 may carry suitable calibrations or markings which, gauging from the top surface of the head, 30 will indicate the vertical position of the piston assembly within the housing, and also the extent to which the packer is constricted at any particular time.

In order that the packing head may also be capable of automatic operation as a blow-out preventer, we also provide a second packer, generally indicated at 64, which renders the contractor 44 responsive to increased fluid pressure in the casing 24, to constrict the main packer 34 about the work. This lower packer 64 preferably will 40 be made to maintain a fairly tight fluid seal between the constrictor 44 and the drill pipe, although some fluid leakage past the packer 64 may occur without disturbing its effectiveness as a blow-out preventer, since the packer and constrictor assembly will necessarily be actuated when a blow-out occurs, because of the great volume of well fluid released under high pressure. The 45 ability of the head to function as a blow-out preventer is of importance in that, for example, should the well develop sudden pressure, the 50 packer 34 is automatically closed as soon as an unbalanced pressure is built up at opposite sides of the lower packer 64. Although provision is made, as will be later described, whereby the 55 operator may close the packer 34 when the well starts to flow or develop pressure, the packing head is made automatically responsive so that if the operator fails to close the packer, it will automatically be closed before any damage can be 60 done. It is to be understood that in certain of its broad aspects, the invention is not necessarily limited to the incorporation of the blow-out preventer feature in the head. It will ordinarily be included, however, since the packing head is particularly 65 designed to operate as a blow-out preventer.

Packer 64, carried by the contractor piston 44 below the upper packer 34, serves primarily to provide a sufficient seal or restriction between the contractor and the work that will cause a more or less sudden increase of fluid pressure in the casing 24 to raise the contractor and constrict the upper packer. The lower packer may be of any suitable type or construction affording a sufficient seal around the work for the purpose stated. In

Figs. 4 to 9 we have illustrated certain forms that may be regarded as typical.

The packer shown at 64 in Fig. 4, and also in Figs. 1 and 2, comprises a packing ring assembly 65 inserted within counter-bore 66 in the lower end of piston 44 and supported on a retaining ring 67. The packer assembly comprises a plurality of rubber rings 68 confined between upper and lower radially distensible metallic rings 70 and 71, each of which comprises a plurality of ring segments 73, typically three, arranged in angularly over-lapping relation as illustrated in Fig. 5, with each segment of the upper ring 70 connected with one each of the lower ring segments directly below, by loosely fitting pins 15 72. Washers 69 are placed about the pins between the rubber rings. As shown in Fig. 2, the bores or rubber rings 68 preferably are at least as small as the outer diameter of the pipe 30, and preferably slightly smaller, so that normally the 20 rubber closely hugs the pipe. The ring assembly is confined between ring 67 and the piston shoulder 74 with sufficient looseness to allow the metal rings 70 and 71 to distend radially as the 25 pipe collar 43a enters the packing, as will now be described.

Assuming the pipe 43 to be raised from the position of Fig. 1 to pull collar 43a upwardly through the packer 64, the flexible rings 68, upon engagement by the end of the collar, are deflected 30 upwardly into the positions shown in Fig. 4, sufficient clearance being provided between the collar and the bores of rings 70 and 71 to provide ample space to receive the inner portions of the packing rings 68 that are folded into them during upward or downward movement of the collar, as the case may be. In addition to being folded or deflected in the condition illustrated in Fig. 4, rings 68 also are subjected to outward radial compression which, in the absence of some provision 35 enabling the rings to yield, might cause the packing injury by the binding action of the collar. This possibility is obviated by making rings 70 and 71 distensible so that as the collar tends to spread the packer, the ring segments 73 also spread 40 apart, as indicated in Fig. 6, to relieve the stress on the rubber but yet allow it to remain in sealing engagement with the collar.

Fig. 7 shows a variational form of lower packer, 45 also of the radially distensible ring mounted type, adaptable for sealing off around either collared or flush joint pipe. In this form, the packing ring assembly, generally indicated at 75, is mounted within counterbore 76 of the contractor piston 77, and comprises an annular rubber packer 78 mounted between radially distensible metallic rings 79 and 80, which in turn are held between annular portions 180 and 181 of the piston 77 and retaining ring 182, respectively. The rings 79 and 80 comprise a plurality of segments 79a and 80a, typically four segments in each ring, having beveled surfaces 183 and 184 seating against surfaces 185 and 186 on the flanges 180 and 181, respectively.

Rings 79 and 80 are interconnected and the 50 packer 78 confined between them, by a suitable number of screws 187 extending through the packer and interconnecting the ring segments. The packer is reinforced and centered relative to the distensible ring assemblies by a suitable 55 number of circularly arranged metal strips 188 projecting into grooves 189 and 190 in the rings 79 and 80. The top surface of the packer 78 is recessed at the inside to fit the shouldered portion 191 of the upper ring 79, the lower surface 75

192 of the packer being tapered in accordance with the angularity of the surface of ring 80 on which it seats.

195 Rings 79 and 80 provide radially distensible backings for the packer 78 when the latter is subjected to outward compression as the pipe collar enters its bore. Thus as the pipe collar, not shown, moves downwardly into the packer, lip 18a and the rubber in the lower portion of the 200 packer, are deflected and compressed outwardly (the collar being larger than the packer bore) in a direction generally paralleling the slope of the lower ring surface 184. As the packer is 205 distended, the lower ring 80 also distends by downward and outward movement of the ring segments 80a along the inclined surface 186, thus 210 keeping the packer in snug engagement with the work, but preventing it from becoming unduly compressed by the collar and thereby subjected 215 to binding and extreme wear. From the described action of the lower ring 80 as the collar passes down through the packer, the capacity 220 of the upper ring 79 for radial distension as the pipe collar is moved upwardly through the packer, will be apparent without the necessity for 225 further detailed description.

Some leakage of fluid past the packer and ring assembly may occur between the ring segments 79a and 80a, but as in the case of the first described lower packer 64, the leakage will be 30 small as compared with the great volume of well fluid released at the time of a blow-out, so that the packer 15 will cause the piston 17 to respond automatically in its packer constricting movement, upon the sudden release of well pressure.

35 Figs. 8 and 9 show a variant form of lower packer designed for collared pipe and having certain particular advantages due to its simple form and ability to withstand rough usage and wear. Here the rubber packer ring 81, loosely held between piston shoulder 82 and ring 83 and rotatable within the contracter, is moulded around a perforated reenforcing metal tube 84, the rubber filling the tube perforations 84a to 40 effectively integrate the metal tube with the packer ring in such manner that the former holds the rubber from "flowing" or gathering as the collar 43a passes through. The packer 81 has an inwardly projecting annular lip 85 engaging the outer surface of the pipe and having a downwardly tapered and rounded upper surface 86 and a lower substantially flat surface 87. It is desired to taper the top surface 86 of the packing lip in order to facilitate downward passage of 45 the pipe collar through the packing against pressure in the casing. By virtue of its shape, the lip 85 is reinforced against and made relatively resistant to upward deflection by the pipe collar so as to effectively withstand any severe conditions of wear that might result from rapidly pulling the collars through it as the pipe string is elevated. Upon engagement by the collar, the lip is doubled upwardly or downwardly, in accordance with the direction of collar movement, 50 into spaces 88 or 89 proportioned to afford ample clearance between the packing and collar to accommodate deflection of the lip, as indicated in Fig. 9, without excessive binding and resultant wear.

55 In Fig. 3 we show a typical manually operated system for selectively communicating high pressure fluid to spaces 50 and 53 within the packing head, for the purpose of controlling the operation of the contracter piston. The operating 60 fluid pressures may be derived from the well cas-

ing 21 via line 90, or from some suitable independent source by way of line 91, these lines being controlled by valves 92 and 93, and connecting with pipe 94. The pressure fluid may be selectively communicated to spaces 50 and 53 under control of a four-way valve, diagrammatically indicated at 95, through lines 96 and 97. Valve 95 operates to connect the space not in communication with the high pressure fluid, with an exhaust line 98.

65 Referring to Fig. 1, it will be noted that the piston assembly, including pistons 44 and 54, provides an upwardly facing pressure area, the top surface of piston 54 exposed to space 53, and two downwardly facing pressure areas, the conical surface 49 of piston 44, and the lower end of this piston including the area of packer 64 between the bore of the retaining ring 67 and the outside of pipe 43. These pressure areas of the piston assembly may be conveniently designated, in the order named, as P_1 , P_2 , and P_3 . As illustrated, the combined areas of P_2 and P_3 is greater than the area P_1 , but P_1 is greater than either P_2 or P_3 , although it is only of importance that P_1 be greater than P_3 .

70 Advantage is taken of the differential pressure areas of the piston assembly as a means whereby the packer 34 may be released from the work, while at the same time releasing movement of the contracter is resisted by fluid pressure within casing 21 acting against pressure area P_3 of the piston. Referring to Fig. 3, assuming line 94 to be in communication with line 90 connecting with the casing, by reversing the position of valve 95 to connect the discharge pipe 98 with space 50 via line 96, the well pressure is applied through line 97 and space 53 against the upper pressure area P_1 of the piston assembly. As stated before, the area P_1 is greater than P_3 , and with the pressure exhausted from space 50, the unbalanced pressure on areas P_1 and P_3 results in 40 downward movement of the contracter and release of the packer 34 from the work.

75 To illustrate the operation of the packing head when the well starts to flow, as for example during drilling or at any other time when the packer 34 normally is open, assume the parts to be in the positions of Fig. 1, with valve 92 open and valve 93 closed, and pipe 91 to be connected with a source of pressure fluid, for example with the circulating fluid pumps, not shown. Valve 95 is thrown to the position illustrated to communicate the pressure fluid to space 50 and relieve pressure from space 53 above the piston. The fluid pressure acting upwardly against pressure area P_2 raises the piston assembly to the position of Fig. 2, and any fluid contained in space 53 is discharged through line 97. With the packer in this position, the pipe 43 may be rotated and moved back and forth between collars 60 during the operation of conditioning the circulating mud in the well to the point where the flow is under control and the packer may be released. It will be understood that where the contracter is independently controlled and operated by fluid 65 pressure from line 94, as we have just explained, the lower packer 64 need not necessarily be used, as the operator has full control in the event of sudden development of pressure in the well.

80 In Fig. 10 of the drawings, we show a variational form of packing head designed particularly to take work of polygonal cross section, such as for example the drive stem 100, although as a matter of fact the previously described head is also capable of packing around work of polygonal 75

cross section despite the use of a circular bore packer 34, since the rubber may readily be contracted to entirely close about work of non-circular cross section. Excessive or destructive wear 5 on the stationary packer, as might be expected, is largely prevented due to the ability to maintain a restricted leakage of lubricating fluid by adjustment of the contractor piston stops, as previously explained. The general construction of 10 the packer head in Fig. 10, and the arrangement of parts are generally similar to the previously described form, except as to the rotational mounting of the packer and its shape characteristics, and, accordingly, similar parts in the two forms are given the same reference numerals. 15 The packer 101 is rotatably mounted on the depending portion 27b' of the head 27, by means of sleeve 102 which rotates within 27b' on bearings 103, and which has a bottom flange 104 also 20 journaled on thrust bearings 105. The packer 101 is attached to flange 104 by reinforcing cables 106, and rotates with the sleeve 102. The latter is rotatably driven by the drive stem 100 by way 25 of a sleeve 107, whose bore shape corresponds to the cross sectional shape of the drive stem, inserted within a correspondingly shaped bore in the upper end of sleeve 102, as illustrated in Fig. 11. Piston 54, which may carry the indicator shown in Fig. 1, is rotatably stationary within 30 the housing and rides on bearings 108 supported by race ring 109, which in turn rests on the upper end of piston 44.

Packer 101 and sleeve 102 rotate with the drive stem 100, and this is of course true whether the 35 packer be in constricted or released condition. And by reason of its frictional engagement with the packer, it may be mentioned that the contractor piston 44 is also caused to rotate with the sleeve and packer assembly. Although the lower 40 end of piston 44 is not shown in Fig. 10, it may carry a lower packer of the type previously referred to in connection with the first described forms of the invention. It will be unnecessary to describe in detail the operation of the form 45 of the invention shown in Fig. 10, since, except for the provision for rotation of the packer and its contractor within the housing, the head operates in essentially the same manner as the previously described form.

50 In Figs. 14 and 15 we show another form of the invention in which a pair of packing heads are mounted in tandem arrangement and provided with operating controls whereby they may be actuated sequentially, dependent upon the direction of movement of the work, to pass collared pipe joints without losing the seal around the pipe. Packing heads 110 and 111, individually similar to the form illustrated in Figs. 1 and 2, are mounted one above the other in spaced relation, the lower head 111 being attached to the 55 casing 112 and connected with the lower end of the housing of the upper head 110, by way of pipe 113 and an adapter 114. The lower end of the adapter is threaded at 115 into the bore of the tubular head 116 of the lower packer. As 60 illustrated, the collared pipe 117 extends through the head assembly, the adapter bore 118 being sufficiently large to pass the pipe collar 117a, but without permitting excessive lateral movement of 65 the collar within the bore.

70 As in the previously described forms of the invention, the contractors within packing heads 110 and 111 are operated by fluid pressure communicated from the casing 112 through line 119, or 75 from an independent source via line 120. Fluid

pressure is communicable from line 121 to the spaces and contractor pressure areas corresponding to 50, 53 and P₂, P₁ in Fig. 1, of the upper head 110, via lines 122 and 123, respectively, and to the corresponding spaces and pressure areas within 5 the lower packing head 111, by way of lines 124 and 125. Manually operated four-way valves 126 and 127 control the application of pressure fluid to the contractors in heads 110 and 111, respectively, and the release of fluid pressure through 10 lines 128, and 129, in the manner previously described with reference to Fig. 3.

A collar operated switch, generally indicated at 130 in Fig. 15, is provided for the purpose of signalling to the operator when the collar 117a has 15 reached a predetermined position between the packing heads, and for purposes to be presently described. The switch 130 comprises a body 131 attached by screws 132 to the side of adapter 114, and a slide block 133 movable laterally within slot 134 in the wall of the adapter and the interior 135 of the body 131. Block 133 is guided between the rollers 136, and carries at its inner end a roller 137 normally riding the surface of the pipe 117 and engageable by collar 117a to shift 20 block 133 laterally to actuate the switch.

Roller 137 is pressed against the pipe by a coil spring 138 encircling a small diameter rod 139 attached to block 133, and projecting outwardly through the packing gland 140. Rod 139 is 25 purposely made small in diameter in order that an excessively heavy spring 138 will not be required to compensate for the pressure differential existing by reason of the high pressure which exists at times within the adapter, and the exposure of the outer end of the rod to 30 atmospheric pressure.

It may be mentioned that the parts of the 35 switch 130 described thus far are generally adaptable for actuating various types of signalling or indicating devices, as well as control systems that are operated by virtue of the engagement of roller 137 by the pipe collar. Hence, the invention is to be regarded as contemplating broadly 40 the use of the laterally shiftable block and roller assembly as an actuating means for any suitable 45 type of signal or control system.

The movement, either upward or downward, of collar 117a within the adapter 114 slightly beyond the point of engagement of roller 137 with the 50 collar, is indicated by a signal light 141 when the contact elements 142 of the switch are closed by rod 139 and roller 137 being pushed outwardly by the pipe collar. Similarly, as the roller rides off the collar, rod 139 moves inwardly to open the 55 switch and the light circuit.

In the operation of pulling the collared pipe string from the well, assume the parts to be in the position shown in Fig. 15 with the packer (corresponding to 34 in Fig. 1) in the lower 60 packing head 111 open, and the corresponding packer in the upper head 110 constricted about the pipe. Upward movement of the pipe from the position of Fig. 15 causes collar 117a to close switch 142 and the signal light circuit. The signal thus given indicates to the operator that collar 117a has passed upwardly through the packer of the lower head 111, and that the lower packer therefore may be closed about the pipe to maintain the seal, and the packer within the 65 upper head 110 opened to pass the pipe collar. The operator thereupon reverses valve 127 from the position illustrated to communicate fluid pressure through line 124 to space 50 and area P₂ of the contractor within the lower packing head 70 75

111, and to raise the contractor piston to close the packer. At the same time, any fluid pressure acting against area P_1 and opposing opening movement of the piston, is released through line 125 to exhaust line 129. After the packer within the lower head 111 is closed, valve 126 is turned to communicate fluid pressure through line 123 against area P_1 of the contractor piston in head 110 to move it downward and open the upper 10 packer. Collar 117a may then be moved upwardly through packing head 110, after which valves 126 and 127 will be operated to again close the packer in head 110 and open the packer in the lower head 111. The above described operations are then repeated during the withdrawal 15 of the next succeeding length of pipe. It will be understood, without the necessity for repetitious explanation, that during the lowering of collared pipe into the well, the two packing 20 heads will be operated in a sequence the reverse of that followed while the pipe is being pulled.

Figs. 16 and 17 show a further variant form of the invention embodying a tandem arrangement of upper and lower packing heads 145 and 146, adapter 147 and collar actuated switch 148, all similar to the corresponding parts previously described with reference to Figs. 14 and 15. The delivery of high pressure fluid from line 149, connecting with the casing 150 via pipe 151 or with 30 an independent source of supply through pipe 152, to packing heads 145 and 146, is controlled by four-way valves 153 and 154, respectively. As in Fig. 14, lines 155 and 156 are communicable with the upper pressure areas P_1 of the contractor pistons, and lines 157 and 158 with the intermediate pressure areas P_2 . Broadly speaking, the valves 153 and 154 may be actuated by any suitable means responsive to operation of the various control switches, as will be explained. 35 Typically, we have shown the valves to be operated by solenoid actuated devices diagrammatically indicated at 159 and 160. These valve operating devices comprise pinions 161, 161a connected in any suitable manner with valves 153, 154, respectively, so that the valves are rotated by rotation of the pinions. Meshing with the pinions are solenoid racks 162, 162a extending within coils 163, 164 and 163a, 164a.

In operation, assume that the pipe 166 is being 50 pulled from the well and that the pipe collar within adapter 147 has reached a position corresponding to Fig. 15. Upon further upward movement, the pipe collar closes switch 148 and the circuit through 161, the solenoid reversing switch 168, and wire 169 connecting with coil 163a of the valve actuating device 160, resulting in upward movement of the rack 162a and reversal of valve 154 from the position shown. As a result, fluid pressure is released from area P_1 55 of the contractor within the lower packing head 146, and the high pressure fluid is communicated through line 158 to pressure area P_2 of the contractor, causing the packer to close about the pipe.

In order to insure that the lower packer will 60 have become closed before the packer within the upper head 145 is opened, the operation of the upper packer is made dependent upon movement of the contractor within the lower head to a 65 position in which it will have fully closed its packer. Mounted on each of the packing heads 145 and 146 is a switch element 170, see Fig. 17, adapted to be contacted by indicator rod 60 carried by the floating piston 54, when the piston 70 reaches the position it normally occupies when

the piston 44 within the head has raised to the position at which the packer is constricted about the pipe. Accordingly, at the point at which the contractor within the lower head 146 has raised to the point of closing the lower packer, switch 170a is closed to energize coil 164 of the valve actuating device 159, via wire 171, switch 168 and wire 172, to pull rack 162 downward and reverse valve 153 from the position illustrated. High pressure fluid then is applied via line 155 against 10 the upper pressure area P_1 of the contractor within head 145 to open the packer, fluid pressure being released from the piston area P_2 via line 157.

The packer below the collar thus having been 15 closed and the upper packer opened, the pipe 166 closed and the upper packer opened, the pipe 166 may then be elevated to withdraw the pipe collar from the upper head 145, after which switch 168 is thrown to the dotted line position and switch 173 closed to energize coil 163 via wire 174, to return the valve actuating device 159 to the position illustrated. Switch 173 then is again opened. As a result of the last mentioned operation of the device 159, valve 153 is operated to close the packer within the upper head 145, and at the point at 25 which the packer has closed about the pipe, switch 170 is actuated to energize coil 164a via wires 174 and 175, to reverse the device 160 and valve 154 to the positions illustrated, and thereby direct the pressure fluid through line 156 to open the 30 lower packer. Switch 168 then is thrown to the full line position, and the above described operations repeated during the removal of the next successive stand of pipe.

In lowering the pipe into the well, assume the 35 lower packing head 146 to be closed and the upper head 145 opened, with switch 168 in the dotted line position. At the point at which the pipe collar is lowered to actuate switch 148, the device 159 and valve 153 first are operated to close the 40 packer within the upper head, and then, after the upper contractor has raised to packer closing position, switch 170 is closed to actuate the device 160 and valve 154, opening the packer within the lower head. When the pipe collar has been lowered through the lower packing head, switch 168 is reversed and switch 173 closed to actuate the device 160 to close the lower packing head, whereupon switch 170a is closed to actuate the device 159 and open the packer within the upper head. 45 Switch 173 then is opened and switch 168 thrown back to the dotted line position, and the described sequence of operations repeated as the succeeding pipe stand is lowered.

We claim:

1. In a packing head applied to a well pipe, a tubular housing adapted to take an elongated member through its bore, a radially contractible packer in the housing and about said member, a packer contractor movable vertically within said housing, means holding one end of said packer against substantial vertical movement in the housing during vertical movement of said contractor, and means for introducing to a space in said housing and substantially closed from communication with said well pipe through the housing bore, fluid exerting a vertically applied pressure against said contractor.

2. In a packing head applied to a well pipe, a tubular housing adapted to take an elongated member through its bore, an annular radially contractible packer in the housing and about said member, a tubular packer contractor engaging the outside of said packer and movable vertically within said housing, and means for intro-

- during to a space in said housing and substantially closed from communication with said well pipe through the housing bore, fluid under pressure to move said contractor vertically within the housing.
3. In a packing head applied to a well pipe, a tubular housing adapted to take an elongated member through its bore, a radially contractible packer in the housing and about said member, a tubular packer contractor movable vertically within said housing and having its lower end exposed to well pipe pressure, and means for introducing to a space in said housing above the lower end of the contractor and substantially closed from communication with said well pipe through the housing bore, fluid under pressure to move said contractor vertically within the housing.
4. In a packing head applied to a well pipe, a tubular housing adapted to take an elongated member through its bore, a continuously annular and radially contractible packer in the housing and about said member, means for stationarily supporting one end of said packer, a packer contractor movable vertically within said housing, and means for introducing into spaces within said housing and substantially closed from communication with said well pipe through the housing bore, fluid under pressure tending to move said contractor in opposite directions.
5. In a packing head applied to a well pipe, a tubular housing adapted to take an elongated member through its bore, a radially contractible packer in the housing and about said member, a packer contractor movable vertically within said housing, means holding one end of said packer against vertical movement during packer contracting movement of said contractor, and means for introducing into and discharging from spaces within said housing and substantially closed from communication with said well pipe through the housing bore, fluid under pressure applied to annular differential pressure areas of said contractor, said areas being formed by opposed surfaces on said contractor of differential radial extent.
6. In a packing head applied to a well pipe, a tubular housing adapted to take an elongated member through its bore, a radially contractible packer in the housing and about said member, a packer contractor movable vertically within said housing and engaging the outside of said packer, and means for introducing into spaces within said housing and substantially closed from communication with said well pipe through the housing bore, fluid under pressure tending to move said contractor in opposite directions, the last mentioned means including means for selectively communicating the pressure within said well pipe to said spaces.
7. In a packing head applied to a well pipe, a tubular housing adapted to take an elongated member through its bore, a radially contractible packer in the housing and about said member, a stationary support above said packer, flexible means embedded within the packer and connected to said support, a packer contracting piston within said housing, and means for moving said piston vertically within the housing.
8. In a packing head applied to a well pipe, a tubular housing adapted to take an elongated member through its bore, a radially contractible packer in the housing and about said member, a packer contracting piston movable upwardly within the housing by the fluid pressure in said well pipe to constrict the packer about said member, adjustable stop means limiting the upward travel of the piston, and means for moving said piston downwardly by fluid pressure to release the packer from said member.
9. In a packing head applied to a well pipe, a tubular housing adapted to take an elongated member through its bore, a radially contractible packer in the housing and about said member, a packer contracting piston in said housing having opposed differential pressure areas exposed to spaces within the housing that are substantially closed from communication with said well pipe through the housing bore, one of said areas being formed by a surface on said piston intermediate its ends, means for selectively introducing fluid under pressure to said spaces to actuate the piston, and means for holding one end of said packer against vertical movement during packer contracting movement of said piston.
10. In a packing head applied to a well pipe, a tubular housing adapted to take an elongated member through its bore, a radially contractible packer in the housing and about said member, a packer contracting piston within said housing and having a downwardly facing pressure area exposed to the pressure in said well pipe, and a second downwardly facing pressure area formed by an annular surface on the piston intermediate its ends, exposed to a space within the housing that is substantially closed from communication with said well pipe through the housing bore, and means for communicating fluid pressure to said space and against the second mentioned piston area.
11. In a packing head applied to a well pipe, a tubular housing adapted to take an elongated member through its bore, a radially contractible packer in the housing and about said member, a packer contracting piston within said housing and having a downwardly facing pressure area exposed to the pressure in said well pipe, a second downwardly facing pressure area, and an upwardly facing pressure area, the last mentioned pressure areas being exposed to separate closed spaces within the housing, and means for selectively introducing fluid under pressure to said spaces.
12. In a packing head applied to a well pipe, a tubular housing adapted to take an elongated member through its bore, a radially contractible packer in the housing and about said member, a packer contractor movable upwardly within the housing to constrict the packer about said member, and a packer carried by said contractor and adapted to cause the latter to move upwardly from a position in which the first mentioned packer is released from pressural engagement with said member, to a position in which said first mentioned packer is pressed into tight engagement with said member, in response to increased fluid pressure in said well pipe.
13. In a packing head applied to a well pipe, a tubular housing adapted to take a collared pipe through its bore, a radially contractible packer in the housing and about said collared pipe, a packer contractor movable upwardly within the housing to constrict the packer about said collared pipe, and a packer carried by said contractor and normally engaging the outside of said collared pipe and having sufficient radial expansibility to pass pipe collars, the last mentioned packer being adapted to cause said contractor to move upwardly from a position in which the first mentioned packer is released from pressural engagement with said collared pipe, to a position in which said first mentioned packer is pressed

- into tight engagement with said collared pipe, in response to increased fluid pressure in said well pipe.
14. In a packing head applied to a well pipe, a tubular housing adapted to take an elongated member through its bore, a radially contractible packer in the housing and about said member, a packer contracting piston within said housing and movable upwardly to constrict the packer about said member, and a packer carried by said piston below the first mentioned packer and engaging the outside of said member.
15. In a packing head applied to a well pipe, a tubular housing adapted to take an elongated member through its bore, a radially contractible packer in the housing and about said member, a packer contracting piston within said housing and movable upwardly to constrict the packer about said member, means holding the upper end of said packer against bodily upward movement within the housing, and a packer carried by said piston below the first mentioned packer and engaging the outside of said member.
16. In a packing head applied to a well pipe, a tubular housing adapted to take an elongated member through its bore, a radially contractible packer contained in the housing and normally spaced about said member, a packer contracting piston within said housing, means for moving said piston downwardly within the housing, and means normally engaging the outside of said member and rendering the piston responsive to sudden increase in the well pipe pressure to radially contract the packer into fluid tight engagement with said member.
17. In a packing head applied to a well pipe, a tubular housing adapted to take an elongated member through its bore, a radially contractible packer in the housing and about said member, a packer contracting piston within said housing and having a downwardly facing pressure area exposed to the pressure in said well pipe, a second downwardly facing pressure area, and an upwardly facing pressure area, the last mentioned pressure areas being exposed to separate closed spaces within the housing, means for selectively introducing fluid under pressure to said spaces, and a packer carried by said contractor and engaging the outside of said member.
18. In a packing head applied to a well pipe, a tubular housing adapted to take an elongated member through its bore, a radially contractible packer in the housing and about said member, a movable packer contracting piston in said housing, a movable member actuated by said piston and extending through the top of the housing above said piston.
19. In a packing head applied to a well pipe, a tubular housing adapted to take through its bore an elongated member of polygonal cross section, a tubular packer in the housing and having a bore adapted to take said member, and a packer contracting piston movable vertically and rotatably within said housing.
20. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; and means for opening one of said packers from closed condition to pass the pipe collar as said pipe is moved longitudinally within said head.
21. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; means for opening one of said packers from closed condition to pass the pipe collar as said pipe is moved longitudinally within said head, and means for indicating movement of the collar to a predetermined position relative to the other packer.
22. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; and means controlled by movement of the pipe collar to a predetermined position for indicating when the pipe collar has passed through one of said packers.
23. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; and fluid pressure operated means for actuating one of the packer contractors to close its packer after the pipe collar has passed through, and for then actuating the other contractor to open its packer.
24. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; and fluid pressure operated means controlled by movement of the pipe collar, for actuating one of the packer contractors to close its packer after the pipe collar has passed through, and for then actuating the other contractor to open its packer.
25. In a packing head applied to a well pipe, the combination comprising a pair of vertically spaced packers each comprising a tubular housing adapted to take a collared pipe through its bore, a radially contractible packer in the housing and about said pipe, and a packer contractor movable vertically within the housing; and means for automatically actuating one of the packers to close its packer after the pipe collar has passed through, and for then automatically actuating the other contractor to open its packer.
26. In apparatus of the character described, the combination comprising a tubular housing connected to a well pipe, a radially contractible packer in the housing and having a bore of substantially circular cross section, fluid under pressure being applied to said packer, a rotatably driven drive stem of polygonal cross section extending through said bore, packer contracting means operable to contract said packer against the flat surfaces of said drive stem, means controllable from the outside of said housing for actuating said contracting means in its packer contracting movement, the drive stem rotating within the packer in its contracted condition, and the extent of packer contraction being limited to maintain a restricted leakage of fluid through the packer bore to lubricate the engagement between the packer and drive stem.
27. In apparatus of the character described, the combination comprising, a tubular housing

connected to a well pipe, a radially contractible rubber packer having a vertically extending bore, means holding said packer against rotation within the housing, a rotating drive stem of polygonal cross section extending through said bore, packer contracting means operable to contract said packer against the flat surfaces of said drive stem, means controllable from the outside of said housing for actuating said contracting means in its packer contracting movement, the drive stem rotating within the packer in its contracted condition, and the extent of packer contraction being limited to maintain a restricted leakage of fluid through the packer bore to lubricate the engagement between the packer and drive stem.

28. In apparatus of the character described, the combination comprising, a tubular housing connected to a well pipe, a continuously annular

rubber packer sleeve exposed at one end to fluid pressure, means holding said packer against rotational movement, a rotating drive stem of polygonal cross section extending through the packer bore, packer contracting means bearing against the outside of the packer and operable to contract said packer against the flat surfaces of said drive stem, means controllable from the outside of said housing for actuating said contracting means in its packer contracting movement, the drive stem rotating within the packer in its contracted condition, and means limiting the extent of packer contraction to maintain a restricted leakage of fluid through the packer bore to lubricate the engagement between the packer and drive stem.
